UNITED STATES PATENT OFFICE.

BERNHARD ZWILLINGER, OF NEW YORK, N. Y., ASSIGNOR, BY MESNE ASSIGNMENTS, TO AMERICAN FUEL AND DISTILLATION COMPANY, A CORPORATION OF NEW JERSEY.

CARBONIZING APPARATUS.

SPECIFICATION forming part of Letters Patent No. 744,666, dated November 17, 1903.

Application filed November 23, 1899. Renewed October 22, 1903. Serial No. 178,153. (No model.)

To all whom it may concern:

Be it known that I, BERNHARD ZWILLINGER, a citizen of the United States, formerly a resident of Ashland, in the county of Ashland and State of Wisconsin, and now a resident of the city of New York, borough of Manhattan, in the county and State of New York, have invented a new and Improved Carbonizing Apparatus, of which the following is a full, clear, and exact description.

My invention relates to apparatus for carbonizing material, such as wood, in a comparatively short time and for saving the valuable gases which are drawn off during the carbonization process, and has for a further object to very quickly cool the carbonized material, whereby the capacity of the plant is materially increased, since it may be recharged with a much smaller delay than hitherto. I hereinafter set forth my invention as carried out in carbonizing the material and carrying away the by-products through the agency of a highly-heated gas, simple or compound, which at least during a part of the operation must be a gas not readily supporting combustion. Air deprived of much of its oxygen and loaded with aqueous vapor is such a gas, as is also ordinary air mingled with a proper proportion of such fixed gases as are set free during and as a result of the carbonizing operation.

In the accompanying drawings I have shown an example of an apparatus embodying my invention, in which—

Figure 1 is a side elevation of such an apparatus, and Fig. 2 is a plan view thereof.

The apparatus comprises as its chief parts a kiln and means for forcing gas therethrough. I also provide means for heating said gas, so as to effect carbonization in the kiln, and, further, I provide a receptacle for the by-products of carbonization. For use in cases where the particular gas employed makes such provision desirable I add devices for depriving the gas used of part of its oxygen and for loading it with aqueous vapor. These latter devices and also the heating devices are arranged to be cut out when not needed. For cooling the carbonized material I provide devices arranged to receive the gases

passing out of the kiln, and the same devices may serve to condense after carbonization such products as are volatile only while heated.

Referring to the particular construction shown in the drawings, K designates a kiln having in its floor a system of perforated pipes K² and provided with a door K⁴.

C is a gas pump or compressor for forcing the gas through the kiln. The gas delivered by the pump may pass through a pipe C' into the lower part of the vessel W, partly filled with water W', supplied continuously through a spraying device W² and kept at a constant level by a siphon W³. The object of this portion of the apparatus is to partly deprive the air of oxygen at the beginning of the operation and to load it with aqueous vapor in cases where air is the gas to be forced initially into the kiln. The gas delivered by the pipe C' after rising through the water and spray passes through a pipe W⁴, provided with a cut-off valve W⁶, into a coil F' in a heating-chamber F and thence through a pipe F² into a vertical drum F³. From this drum the gas passes through a pipe K' to the perforated pipes K², which discharge it through their apertures into all parts of the lower portion of the carbonizing chamber or kiln. From this chamber the gas and the volatile products of the carbonizing process escape through a pipe K³, pass a water seal in a vessel D, and are conveyed to coils R R in a circulating bath of cold water, whence they pass into a closed receptacle B. This vessel and siphon carries such material as has been condensed in liquid form to another vessel B² to be disposed of as may be desired, while the more permanently gaseous products pass through a pipe B³ to a suitable reservoir G. By closing a valve near the lower end of the pipe B³ (see Fig. 1) and opening a by-pass at B⁴ the fixed gases are made to pass directly to the reservoir without entering the receptacle B. If the gas supplied to the compressor does not consist exclusively or largely of atmospheric air, it need not of course be sent through the water and spray, although I consider it preferable to do so in any event, for the reason that even if the gas has the proper

low percentage of oxygen the charging of this gas with aqueous vapor will be of advantage in that it will act as a protection against overheating of the coil F'.

5 Practically it is convenient to supply the pump with the gases collected in the reservoir G, and for this purpose a pipe G' is shown as leading from the reservoir to the pump. Where the pump thus draws its supply from the reservoir, the apparatus need not be first filled with gas not a supporter of combustion, for if the pump first delivers ordinary air much volatile matter will be given off by the material in the kiln before 10 combustion can begin, and hence the mixture of gas and vapor which the pump circulates through the apparatus becomes incapable of supporting combustion before the matter in the kiln reaches the point of ignition. The 15 temperature in the kiln is indicated by a pyrometer T, extending into the drum F³. In addition to the devices already described a valved by-pass pipe W⁵ leads from the vessel W around the heating devices at F to the 20 drum F³, and a second valved by-pass pipe C² leads from the pipe C' around the vessel W to the pipe W⁵ at a point between its valve and the drum. By this arrangement it is possible to cut off the heating device alone 25 or both that device and the devices for reducing the gas and charging it with vapor.

The drum F³ is provided with a valve F⁴ on the top of the kiln capable of being operated from without the kiln, and if this valve 30 be opened gas is discharged into the top of the kiln as well as through the perforated pipes J² on its floor. If it should be desired to allow the gas to escape from the kiln without passing through the cooler, the pipe Y 35 may be opened at Z. It is obvious that the gas pumped through the kiln for cooling it need not be the gas stored in the reservoir, but may be any suitable gas, ordinary atmospheric air being appropriate if it be sent 40 through the device at W. It is equally clear that if the cooler be adequate a small quantity of gas stored in the reservoir will be quite sufficient, since the same gas makes repeated circuits, each time giving up in the 45 cooler the heat which it has just taken from the kiln.

I effect a considerable saving of time in my invention by pumping through the kiln cooling-gases which are not supporters of combustion, and I find that the time required for cooling may by this procedure be shortened 50 practically to the same extent as the time needed for carbonizing.

I desire it to be understood that various

modifications may be made without departing from the nature of my invention.

I claim as my invention and desire to secure by Letters Patent—

1. In a carbonizing apparatus, the combination with a closed kiln, of a conduit leading from the kiln, a compressor, the inlet of which is connected with said conduit, a cooler located in the path of the gas between the kiln and the compressor, a vessel connected with the outlet of the compressor and adapted to hold water to partially deoxygenize any air that may be fed by the compressor, and to charge it with aqueous vapor, a heater connected with the outlet of said vessel, and a connection from the outlet of said heater to the inlet of the kiln so that a mixture of gases and air partially deoxygenized and charged with aqueous vapor will be forced into the kiln at the beginning of the operation.

2. In a carbonizing apparatus, the combination with a closed kiln, of a conduit leading from the kiln, a compressor, the inlet of which is connected with said conduit, a cooler located in the path of the gas between the kiln and the compressor, a vessel connected with the outlet of the compressor and adapted to hold water to partially deoxygenize any air that may be fed by the compressor and to charge it with aqueous vapor, a heater connected with the outlet of said vessel, and a connection from the outlet of the heater to the inlet of the kiln, so that a heated fluid partially deoxygenized and charged with aqueous vapor will be forced into the kiln at the beginning of the operation.

3. In a carbonizing apparatus, the combination with a closed kiln, of a conduit leading from the kiln, a compressor, the inlet of which is connected with said conduit, a cooler located in the path of the gas between the kiln and the compressor, a deoxygenizing apparatus located between the compressor and the kiln, and adapted to deoxygenize any air that may be fed by the compressor so that the gaseous fluid may pass through the said apparatus on its way from the compressor to the kiln, a heater between the deoxygenizing apparatus and the kiln and a direct connection from the compressor to the kiln and means for leading the gaseous fluid derived by the carbonization of the wood through said direct connection or through the deoxygenizing apparatus and the heater.

BERNHARD ZWILLINGER.
